UNITED STATES PATENT OFFICE.

DAVID L. B. PETERSON, OF EAST ORANGE, NEW JERSEY.

DESIGN FOR A DESK-BOX.

SPECIFICATION forming part of Design No. 34,787, dated July 16, 1901.

Application filed April 15, 1901. Serial No. 56,014. Term of patent 7 years.

To all whom it may concern:

Be it known that I, DAVID L. B. PETERSON, a citizen of the United States, residing at East Orange, in the county of Essex and State of New Jersey, have invented and produced a new and original Design for a Desk-Box; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

Figure 1 is a perspective view, and Fig. 2 is a rear elevation, of my newly-designed desk-box.

As shown in the drawings, the leading feature of my design consists in a desk-box having in front elevation an oblong rectangular outline and within the rectangular outline an oblong rectangular opening, the longer sides of which are parallel with the longer lines of the said oblong rectangular outline of the attachment, the space between one of the said longer lines and the said oblong in-

ner opening being ornamented with a series of round openings.

In said drawings, *a* indicates the body portion of a desk-box of my new design, and *b* the front of the same, said front being oblong rectangular in outline. Within the outlines of said front *b* is an oblong rectangular opening *d*, the longer sides of which are parallel to the longer lines of the outline of the front. Between said oblong opening *d* and one of the parallel lines of the outline of the front *b* is a series or row of round openings *c c c c*. Near the opposite ends of the front *b* are circular apertures *e*, and in the corners of the rectangular outline of said front are perforations *f*.

What I claim as new is—

The design for a desk-box as herein shown and described.

In testimony that I claim the foregoing I have hereunto set my hand this 14th day of February, 1901.

DAVID L. B. PETERSON.
